Primary Examiner — Sheryl Lane*Assistant Examiner* — Stacey L Hopkins(74) *Attorney, Agent, or Firm* — Innovation Capital Law Group, LLP; Vic Lin(57) **CLAIM**

The ornamental design for a flashlight, as shown and described.

DESCRIPTION

FIG. 1 is a front view of a flashlight showing my new design; FIG. 2 is a rear view thereof; FIG. 3 is a left side view thereof; FIG. 4 is a right side view thereof; FIG. 5 is a top view thereof; FIG. 6 is a bottom view thereof; FIG. 7 is a front perspective view thereof; and, FIG. 8 is a rear perspective view thereof. The broken lines in the drawings illustrate portions of the flashlight that form no part of the claimed design.
